VORTICAL GASEOUS-FLUID TYPE CLASSIFIER FOR PULVERIZED SOLID PARTICLES

William A. Thomas, Pittsburgh, Pa., assignor to Blaw-Knox Company, Pittsburgh, Pa., a corporation of New Jersey

Application February 15, 1946, Serial No. 647,670

6 Claims. (Cl. 209—144)

1

This invention relates to the grinding or pulverizing of solids in an intermediate state of subdivision by impact of the particles with each other and the walls of an endless passage through which they are driven by a suitable motive fluid. In particular, the invention relates to means for separating the particles which have been reduced to sufficiently small size from the remainder of the circulating particles and delivering them to a point of use while returning the oversize particles for further grinding.

Impact grinders or pulverizers of the endless-passage type have been known for some time but have been found to be subject to serious limitations in respect to capacity, the amount of steam required and the control of the size of the product. In addition, the delivery of the product is pulsating and not continuous. It is impossible to pulverize material having a substantial moisture content in the known apparatus and the latter requires considerable time for gradual shutdown.

I have invented a novel pulverizing apparatus which avoids the aforementioned objections to apparatus of the same general type known heretofore. In a preferred embodiment, I provide a pulverizer of the continuous-passage type with a classifier adapted to be connected in circuit therewith, capable of separating the particles which have been reduced sufficiently in size from those which require further grinding. The classifier preferably comprises a housing adapted to be connected to the members forming the continuous passage of the grinder or pulverizer so that a descending stream of gas with particles entrained therein is delivered to the top of the classifier. A spreader cone is located in the upper portion of the housing and has a cylindrical baffle or skirt depending therefrom. An outlet duct leads from the cone to the exterior of the housing. A hopper located below the cone and within the baffle collects oversize particles and returns them to the pulverizer. A series of vertical guide vanes spaced around the interior of the baffle impart a circumferential velocity component to the inwardly flowing gas, thereby facilitating separation of the oversize particles from those which have been sufficiently reduced in size. The latter float in the gas and are conveyed by the outflowing stream thereof through the outlet duct.

A complete understanding of the invention may be obtained from the following detailed description when read in connection with the accompanying drawings illustrating the preferred embodiment. In the drawings,

Figure 1 is a side elevation showing the invention in operative relation to means for supplying solid fuel to be ground and means for delivering the ground fuel to a combustion space;

2

Figure 2 is an elevation of the grinder to enlarged scale, partly broken away and partly in section along a central vertical plane;

Figure 2a is a vertical section through an injector for delivering to the grinder the material to be ground;

Figures 3 and 4 are transverse sectional views taken along the plane of lines III—III and IV—IV, respectively, of Figure 2; and

Figure 5 is a partial vertical section taken through the outlet duct.

Referring now in detail to the drawings and, for the present, to Figure 1, solid material to be ground, in the particular application illustrated, coal of a suitable grade, is stored in a bin 10 from which it is delivered by a screw conveyor 11 to the inlet 12 of an injector 13. A motor-reducer 10a drives the conveyor and an agitator 11a in the bin 10.

The injector 13 delivers the coal into the upper portion of an impact grinder 14 of the endless-passage type shown in Figures 6 and 7 of Kidwell Patent 2,219,011. The grinder includes a classifier 15 from which coal of the desired degree of fineness flows through pipe 16 to a separator 17, being entrained in a stream of motive fluid such as steam. The separator delivers the coal downwardly to a burner 18 from which it is discharged into a combustion space 19 by a stream of air delivered to the burner from a blower 20 through suitable piping 21. The steam from which the coal has been largely separated is discharged from the separator through a pipe 22 to the combustion space.

The classifier 15 is illustrated in detail in Figures 2 through 4 along with the injector 13 and the pulverizer 14. The injector includes a Venturi throat 23 between the inlet 12 and the upper portion of the grinder. A scraper 25 is mounted for rotation in the inlet 12 about the axis of the steam nozzle 26 of the injector to prevent accumulation of material at the entrance end of the Venturi throat. The shaft of the agitator 11a is prolonged and drives the scraper 25 in the inlet 12 through bevel gears 12b. This portion of the apparatus is disclosed in greater detail and claimed in my copending application Serial No. 637,819 filed December 29, 1945, Patent No. 2,420,388, for Apparatus for feeding granular material into a fluid stream.

The injector discharges coal into the upper portion of the grinder 14. The lower portion of the grinder is formed by a jet tube 24 which is an elbow having steam nozzles 28 spaced therealong adapted to deliver jets for driving the coal particles repeatedly around the grinder 14. The latter also includes an arcuate tube 29 with a connection for the injector, and connecting members 30 and 31. These several members form a con-

tinuous passage the sectional area of which increases gradually in the direction of the flow.

The classifier 15 comprises a housing 32 having its upper end connected to the outlet end of the tube 29 and its lower end to the entrance end of the tube 24. The housing has generally the shape of two conical frusta disposed coaxially with their bases adjacent each other but spaced apart and a cylindrical wall therebetween. A spreader 33 in the form of a conical frustum is disposed in the upper portion of the housing and has a cylindrical baffle or skirt 34 depending from the lower edge thereof. A renewable wear plate 33a is placed on the frustum to withstand the impact of particles emerging from tube 29. A hopper 35 is supported in the lower portion of the housing on radial brackets 36. A series of vertical guide vanes 37 is disposed between the hopper and the spreader cone. The vanes have vertical hinge pins, the lower ends of which are journaled in a ring 38 carried by the hopper. The upper ends of the hinge pins are journaled in a base plate 39 secured to the cone 33. The cone 33 and baffle 34 are thus supported on hopper 35. A ring 40 rests on the upper ends of the vanes 37. Projections 41 at the inner edges of the vanes extend into radial slots 42 spaced circumferentially of the ring 40. It is thus possible to adjust all the vanes 37 simultaneously by rotating the ring 40. For this purpose, the hinge pin of one of the vanes has an extension 43 projecting downwardly therefrom and through the lower portion of the housing. A lever 44 permits the extension 43 to be turned by hand for effecting the desired adjustment of the vanes 37.

The base plate 39 has a central opening therethrough from which a tubular neck 45 depends. An outlet passage 46 extends from the cone 33 to the adjacent wall of the housing and connects with an elbow 47. As shown in Figure 1, the delivery pipe 16 communicates with this elbow. A helical flight or vane 48 extends around inside the hopper 35 to cause the particles and steam moving circumferentially of the hopper to descend through the open lower end thereof and re-enter the tube 24 of the pulverizer.

The operation of the apparatus is as follows. Coal introduced into the tube 29 by the injector 13 is subjected to impact the plate 33a and, after passing the classifier 15 with the result to be explained, against the walls of the endless passage formed by the members 24, 29, 30 and 31 of the grinder 14. The particles are driven along a continuous course by the jets from the nozzles 28 and are delivered by entrainment in the resulting stream to the upper end of the housing 32. The stream of steam and coal particles striking the plate 33a and cone 33 are spread laterally in all directions. Some of the steam and the finer particles entrained thereby flow around the lower edge of the baffle 34 and inwardly between the vanes 37 toward the central outlet through neck 45. As the steam passes around the lower edge of the baffle 34, the larger and heavier particles continue on a downward course falling into the lower portion of the housing and returning to the entrance of the tube 24. The steam and particles which pass between the vanes 37 have a circumferential motion imparted thereto by the angular adjustment of the vanes whereby a vortex is created in the upper portion of the hopper 35. From the center of the vortex a column of steam ascends through the neck 45 carrying with it the particles of coal which have been reduced to such a size as to float in the outflowing stream. The

stream flows from the cone 33 through the outlet 46, through elbow 47 and thence by pipe 16 to the separator 17. The larger, heavier particles which pass between the vanes 37 fall downwardly as they travel about the hopper. On striking the helical vane 48, these particles are given a positive downward velocity component and are thereby discharged into the entrance end of the tube 24.

It will thus be apparent that the device effects a two-stage separation of the coal which has been sufficiently reduced in size for combustion. The first separation occurs when a portion of the steam entering the classifier sweeps around the lower edge of the baffle 34. The second stage occurs within the hopper 35, as a result of the circumferential velocity component imparted to the steam and entrained coal particles by the angular adjustment of the vanes 37.

The mixture of steam and coal particles delivered to the separator 17 from the classifier 15 is divided thereby into a stream of finely divided coal falling into the burner 18 and a stream of steam with a small percentage of coal delivered through pipe 22 into the combustion space 19.

The helical vane 48 is an important feature of the classifier because it produces a down draft of steam and oversize particles through the hopper 35, thus preventing an up draft through the hopper which might tend to be produced by direct flow of steam around the cone 33, the baffle 34 and the hopper and into the bottom of the latter.

The operation of the classifier may be summarized thus. In the space between the housing and the baffle 34, the coarser particles are separated by the differential in their mass weight as a result of their inertia. This separation is possible because of the reduced velocity of the steam resulting from the large sectional area of the annular passage through the classifier as compared to that of the passage through the grinder. The coarse particles continue undeflected and re-enter the grinder for further reduction in size. The steam carrying the smaller particles rises inside the baffle 34 and is subjected to a second separation resulting from the tangential motion imparted by the vanes 37. In this centrifugal separation, the finest particles float on the ascending stream through the outlet while the coarser particles circle around in the hopper and are positively directed downwardly by the vane 48.

The apparatus of my invention has several important advantages over impact pulverizers as known heretofore. In the first place, I am enabled, by my invention, to deliver a greater quantity of finely ground material than has been obtainable heretofore from continuous-passage impact grinders. This seems to result from the fact that the velocity of the circulating steam is reduced in the region where the separation occurs as a result of the enlargement of the sectional area of the passage. My invention also makes it possible to grind a given amount of material with a smaller amount of steam. The delivery of the finely ground material, furthermore, is steady and continuous, and free from the pulsations characterizing the operation of apparatus known before. The apparatus of my invention is also capable of pulverizing materials having a substantial moisture content. This was impossible with the prior apparatus. It is also possible to shut down the pulverizer according to my invention much more quickly than those known previously.

My invention also has the characteristic of delivering material of substantially the same degree

of fineness regardless of the rate of feed. This is not true of previous grinders which exhibited a marked change in the fineness of the product if the feed rate is changed materially, the particle size becoming larger as the feed rate is increased. On the contrary, the apparatus of my invention exhibited but very small changes in the percentages of various sizes of particles when the feed rate was varied over a substantial range. This is particularly important in combustion applications since it is frequently desirable to operate at reduced rates without affecting combustion conditions seriously. Considering the entire system as applied to the production of pulverized coal for combustion, the removal of steam in the separator permits cold air to be supplied to the burner without objectionable condensation.

The location of the feed-in connection above the classifier increases the rate of grinding which is particularly important in the case of the harder coals. It also gives better drying of the coal and some initial separation of fines because the entering coal makes one pass through the classifier before grinding begins (except that due to striking the plate 33a).

Fundamentally, my invention makes it possible to withdraw from the grinder substantially all the material which has been ground to the desired fineness. It differs in this respect from grinders previously known in which it was impossible to withdraw a substantial portion of the material which had been sufficiently reduced in size. In the embodiment illustrated, my invention removes from the grinder all coal which is in a state of subdivision sufficiently small for use as pulverized fuel. My invention is not only capable of being shut down more quickly than previous grinders but also makes it possible to start up combustion in a much shorter time.

While the invention has been described by reference to a system for the production of pulverized coal for combustion, it will be understood that this is merely by way of example since the apparatus may be used for grinding material other than coal.

Although I have illustrated and described but a preferred embodiment of my invention, changes in the details of construction disclosed may be made without departing from the spirit of the invention or the scope of the appended claims.

I claim:

1. In combination, a classifier for separating particles of granular material adapted to be connected in closed-circuit relation with an impact pulverizer of the endless-passage type delivering downwardly therefrom a stream of gas entraining particles of various sizes, said classifier comprising a housing converging toward its upper and lower ends, said ends being connected to points spaced apart along the pulverizer and forming a portion of said endless passage, a downwardly flaring spreader cone in the upper portion of the housing adjacent the gaseous fluid inlet thereto, a skirt depending from the cone, a series of vertical guide vanes spaced around the skirt and spaced inwardly therefrom, a passage between said vanes and the interior of said cone, an outlet leading from said interior of said cone to the exterior of said housing, and a hopper in the lower portion of said housing and below said guide vanes for returning oversize particles to the pulverizer.

2. In combination, a classifier for separating particles of granular material adapted to be connected in close-circuit relation with an impact

pulverizer of the endless-passage type delivering downwardly therefrom a stream of gas entraining particles of various sizes, said classifier comprising a housing converging toward its upper and lower ends, said ends being connected to points spaced apart along the pulverizer and forming a portion of said endless passage, a fixed downwardly flaring spreader cone in the upper portion of the housing adjacent the gaseous fluid inlet thereto, a series of vertical guide vanes for said gas-entrained particles spaced around the axis of the cone and lying below the cone and within the projection of the base thereof on a horizontal plane, said guide vanes being angularly disposed with respect to the respectively adjacent radii of said cone, a passage between said vanes and the interior of said cone, an outlet leading from said interior of said cone to the exterior of said housing and a hopper in the lower portion of said housing and below said guide vanes for returning oversize particles to the pulverizer.

3. In combination, a classifier for separating particles of granular material adapted to be installed in a descending stream of gas entraining particles of various sizes in an impact pulverizer of the endless-passage type, comprising, a housing for said classifier forming a portion of said endless passage, a fixed downwardly flaring spreader cone in said housing adjacent the gaseous fluid inlet thereto, a cylindrical baffle coaxial with said cone and extending downwardly therefrom, a passage extending between the interior of said baffle and said cone, an outlet duct communicating with said cone for conducting outflowing gas and particles floating therein, a hopper within said baffle coaxial therewith and smaller in diameter than the baffle for collecting oversize particles falling through the gas, guide vanes for said gas entrained particles above the hopper for directing the gas entering the space between it and the baffle in a direction circumferentially of the hopper, and an opening in the bottom of said hopper through which said oversize particles are returned to the material passing through said endless passage beyond said classifier.

4. In combination, a classifier for separating particles of granular material adapted to be connected in closed circuit relation with an impact pulverizer of the endless-passage type delivering downwardly therefrom a stream of gas-entrained particles of various sizes, comprising, a housing forming an enlarged portion along the length of said axial passage, a fixed frusto-conical spreader concentrically positioned within said housing adjacent the gaseous fluid inlet thereto, a cylindrical skirt substantially depending from the lower edge of said spreader, a hopper concentrically positioned within said cylindrical skirt and spaced therefrom, a depending tubular neck positioned within said spreader in concentric relation thereto and above said hopper, means defining a plurality of generally radial passages extending between the interior surface of said skirt and the interior of said hopper adjacent the upper portion thereof an outlet in communication with said tubular neck and extending through said housing, a downwardly directing helical vane in the lowermost portion of said hopper, said hopper having an axial opening below said vane, whereby gas-entrained fine particles make a reentrant turn beneath said skirt and enters said hopper wherein the predetermined finer portion thereof passes out through said neck and said outlet and the coarser portion thereof passes out through

said opening at the bottom of said hopper to rejoin material moving through said endless passage.

5. In combination, a classifier for separating particles of granular material adapted to be connected in closed circuit relation with an impact pulverizer of the endless-passage type delivering downwardly therefrom a stream of gas-entrained particles of various sizes, comprising, a housing forming an enlarged substantially vertical portion along the length of said axial passage, a fixed frusto-conical spreader concentrically positioned within said housing adjacent the gaseous fluid inlet thereto, a hopper coaxially positioned beneath said spreader and spaced therefrom, a depending tubular neck positioned beneath said spreader in concentric relation thereto and above said hopper, means defining an annular passage extending between the base of said spreader and the interior of said hopper adjacent the upper portion thereof, said annular passage being above the bottom of said tubular neck, centrifugal guiding means in said annular passage, and an outlet in communication with said tubular neck and extending through said housing, said hopper having an axial opening in the bottom thereof, whereby gas-entrained fine particles enter said hopper beneath said spreader with a whirling motion and make a reentrant turn around the bottom of said neck wherein the predetermined finer portion thereof passes out through said neck and said outlet and the coarser portion thereof passes out through said opening at the bottom of said hopper to rejoin material moving through said endless passage.

6. In combination, a classifier for separating particles of granular material adapted to be connected in closed circuit relation with an impact pulverizer of the endless-passage type delivering downwardly therefrom a stream of gas-entrained particles of various sizes, comprising, a housing forming an enlarged substantially vertical portion along the length of said axial passage, a fixed frusto-conical spreader concentrically positioned within said housing adjacent the gaseous fluid inlet thereto, a hopper coaxially positioned be-

neath said spreader and spaced therefrom, a depending tubular neck positioned beneath said spreader in concentric relation thereto and above said hopper, means defining an annular passage extending between the base of said spreader and the interior of said hopper adjacent the upper portion thereof, said annular passage being above the bottom of said tubular neck, centrifugal guiding means in said annular passage, an outlet in communication with said tubular neck and extending through said housing, said hopper having an axial opening in the bottom thereof, and a downwardly directing helical vane around the inside of said hopper adjacent said axial opening, whereby gas-entrained fine particles enter said hopper beneath said spreader with a whirling motion and make a reentrant turn around the bottom of said neck wherein the predetermined finer portion thereof passes out through said neck and said outlet and the coarser portion thereof passes out through said opening at the bottom of said hopper to rejoin material moving through said endless passage.
